CONTAINER WITH AN INFOLDED BOTTOM CLOSURE

Arthur J. Seiple, Perryburg, Ohio, assignor to Ex-Cell-O Corporation, Detroit, Mich., a corporation of Michigan Filed Apr. 2, 1962, Ser. No. 184,230 5 Claims. (Cl. 229—37)

This invention in general relates to paperboard container bottoms and particularly to the infold bottom closure style of container.

Coated paperboard containers are being used in increasing quantities as fluid containing bottles in place of other commonly used means. The success of this new container has caused much demand for new and various sizes. At the present time the largest size coated paperboard container in general use holds a half gallon of fluid. As the sizes continue to increase and use varies, certain characteristic of the container is required to be modified to give satisfactory service. Milk is now shipped many miles from bottling plants and in normal transportation methods is subjected to continuous vibrations. In many of the present containers there is overhang of the main body and side walls over the bottom panel members. This causes a bellows actions at the bottom of the container between the bottom panels and the side walls. The bellows action can cause a failure of the container by the coating becoming fatigued and cracking, thus, allowing the fluid to leak out of the container.

The major objective of the present invention is to provide a bottom structure such that there is not a bellows action between the side walls and the bottom panels.

Also, the objective of the present invention includes the provision of a container construction capable of accomplishing the above objectives with a minimum of material cost and fabricating expense, and at the same time being composed of simple and ruggedly formed structure which is very reliable in application.

Other objectives and advantages of the invention will be apparent from the following detailed description and claims, taken in connection with the accompanying drawings which form part of the instant specification, and which are to be read in conjunction therewith, and in which like reference numerals are used to indicate like parts in various views.

FIG. 1 is a layout view of a inside surface of a container blank showing the inventive structure;

FIG. 2 is a perspective view of a container fabricated from the blank shown in FIG. 1;

FIG. 3 is a side elevation of the container shown in FIG. 2;

FIG. 4 is a sectional view showing the inside bottom structure taken on the line 4—4 of FIG. 3;

FIG. 5 is a view showing the outside bottom structure taken on the line 5—5 of FIG. 3;

FIG. 6 is enlarged exaggerated view showing a typical corner generally indicated as FIG. 6 in FIG. 4;

FIGS. 7, 8, 9 and 10 are fragmentary perspective views illustrating sequentially the various steps in forming the bottom closure of the container of FIG. 2;

FIG. 11 is a flat side seamed blank made from the blank shown in FIG. 1 and showing the outside surface thereof.

While the invention is susceptible of various modifications and alternative constructions, certain illustrative embodiments have been shown in the drawings and will be described below in considerable detail. It should be understood, however, that there is no intention to limit the invention to the specific forms disclosed, but on the contrary, the intention is to cover all modifications, alternative constructions and equivalents falling within the

2

spirit and scope of the invention as expressed in the appended claims.

Referring generally to the figures, we have a flat blank form 10 shown in FIG. 1 with a pattern of appropriate score lines and having the inside surface of the blank showing. The container is separated into three groups by staggered score lines 11 and 12. The material above score line 11, as seen in FIG. 1, is the top closure, a discussion of which is not necessary for disclosure of the present invention, however, a complete disclosure is given in a copending application U.S. S.N. 122,571, filed July 7, 1961. The material between score lines 11 and 12, as seen in FIG. 1, is the body and comprises four panels, 13 through 16 and side seam flap 17. The body group is defined on the sides by edges 18 and 19 and with the panels being separated by score lines 21 through 24. The material below score line 12, as seen in FIG. 1, is the bottom closure group and comprises major bottom closure flaps 25 and 27, first minor bottom closure flap 26, second bottom closure flap 28 and side seam flap 17. The bottom closure group is defined on the sides by edge 18 and 19 and the flaps are separated by the score lines 21 through 24. The major flap 25 has an extended tuck-in member 31 and major flap 27 has an extended tuck-over member 32. The first minor flap 26 is flanked by trapezium fold-back members 33 and 34 and connected thereto by score lines 35 and 36 respectively. The second minor flap 28 is flanked by trapezium fold-back members 37 and 38 and connected thereto by score lines 41 and 42 respectively.

To construct a container as shown in FIG. 2 from the blank in FIG. 1, a flat side seamed blank 10 is formed as viewed in FIG. 11. To form a flap side seamed blank, panel 16 and the side seam flap 17 would be folded about score line 23 until their inside surfaces contact the inside surfaces of panels 15 and 14 respectively. The panel 13 would be folded about score line 21 so that its inside surface contacts the inside surface of panel 14 and the outside surface of side seam flap 17. The inside surface of panel 13 along edge 18 which will contact the outside surface of side seam flap 17 and the outside surface of flap 17 will be heated to activate their coating if coated with a heat sealable material or glue material may be applied to this surface so they will be bonded together.

The container blank 10 as shown in FIG. 11 is in the form in which it will be fabricated on packaging machines, for example the unit disclosed in U.S. Patent No. 3,002,328 which issued October 3, 1961. To form the bottom, the container blank 10 is opened up into a tubular form as seen in FIG. 7. To make the bottom, the major flaps 25 and 27 are moved towards each other. Also, the minor flaps 26 and 28 are moved towards each other. This causes fold-back member 38 to rotate around score line 24 so that the inside surfaces of member 38 and flap 25 are coming together. At the same time and during the same movement member 38 is rotating around score 42, thus the outside surfaces of member 38 and flap 28 are coming together. Fold-back members 33, 35, and 37 make the same movements as member 38 with panels 25—26, 27—26 and 27—28 respectively. Bottom closure major flap 25 moves towards bottom closure major flap 27 just enough faster than flap 27 moves towards flap 25 so that tuck-in member 31 is positioned between fold-back members 33—38 and major flap 25. The relative movements of the parts can be seen in FIGS. 7 through 10. FIG. 10 shows the bottom when completely closed. If the container is pre-coated with heat sealable material the bottom flaps can be heated to activate their coating to form a bonded surface when joined together. If the container is not of the pre-coated type bonding material may be applied to the flap areas which meet when the bottom is formed so they will bond when they meet.

The score lines 12, 35, 36 and 12, 41, 42 on flaps 26 and 28 respectively form isosceles triangles with the intersection of the score lines 35, 36, 41 and 42 with score line 12 a predetermined distance from the score lines 21, 22, 23 and 24 respectively. The triangle on flap 26 has equal legs 35 and 36 with their intersection 51 on the bottom edge 20 of the blank 10 and equal distance from the score lines 21 and 22. The triangle on flap 28 has equal legs 41 and 42 with their intersection 52 on the bottom edge 20 of the blank 10. Score line 41 and 42 intersect score line 12 at predetermined distances from score lines 23 and 24 respectively which are not equal. The intersection of lines 12 and 42 is further from score line 24 than the intersection of lines 12 and 41 is from score line 23. However, in our example, the distance from score line 23 to the intersection of lines 12 and 41 is equal to the distances score lines 21 and 22 are from the intersection of lines 12—35 and 12—36 respectively. Therefore, the intersection 52 will not be equal distance from score lines 23 and 24 but will be closer to 23 than 24. The distances from line 12 to intersections 51 and 52 will be just short of half the distance between lines 22 and 23. The purpose of this will be explained further in the specification.

FIGS. 2 and 3 show the container as it appears after being completely constructed. FIG. 4 shows a view of the bottom closure as seen from the inside of the container. Intersections 51 and 52, as seen in FIG. 4, will be just touching or just short of contacting. This will require panels 14 and 16 to be close enough together that will not form an overhang at score line 12 of flaps 26 and 28 respectively. This occurs because the distances from the intersections 51 and 52 to score line 12 are equal and just less than half of the distance from score lines 22—23 and 21—24 as constructed. FIG. 5 shows the appearance of the bottom closure as viewed from the outside of the container. As seen in this view the panels 14 and 16 do not overhang the score lines 21—22 and 23—24 respectively. By having the intersection of the score lines 35 and 36 with line 12 not at the intersection of score lines 21 and 22, respectively, with line 12 but a predetermined distance from their intersection, as seen in FIG. 1. The intersection of the score lines 41 and 42 with line 12 will not be at the intersection of score lines 23 and 24, respectively, either, but they will be a predetermined distance from their intersection, as seen in FIG. 1, and the distance for 42 will be greater than that for 41. These distances allow the flaps 26 and 28 to swing into the container when the bottom is being formed, as seen in FIGS. 7 through 10 without forcing a large amount of paper into each corner of the container bottom as would be the case if the score lines intersected at the same location. The intersection of score lines 42 and 12 is a further distance than the other score line intersections because at this point more room must be allowed for the paper due to the location of the side seam flap 17, if the container had its side seam in the middle of one panel section this distance could be equal to the other distances. FIG. 6 shows an enlarged view of the bottom corner formed at score line 23. It can be seen how the score line 41 starts towards the center of the container just to one side of the inside bulge of score line thus preventing the score from forcing the flap 28 away from the center of the container and in this way holding the container panel 16 back so it forms an overhang as to bottom closure flaps. The predetermined distances of the intersection of score lines 35, 36, 41 and 42 are based on the thickness of the container paper-board being used. An example of sizes and dimensions that could be used would be a liquid gallon container having a width of panel 15, the distance from the middle of score line 22 to the middle of score line 23, of 5.531 inches and all other panels equal to this except panel 13 which will be .040 of an inch shorter with the additional length of this wall of the container coming from the side

seam flap 17. The distances from intersections 51 and 52 to the middle of score line 12 being 2.750 inches. The thickness of the container walls being .028 of an inch. The distances of the intersections of score lines 35, 36 and 41 with score line 12 from score lines 21, 22 and 23 respectively being .125 of an inch and the distance of the intersection of score line 42 with score 12 from score line 24 being .187 of an inch.

When the container is constructed and the two intersections 51 and 52 meet, there will be a distance of 5.500 inches from the score line 12 on flap 26 to the score line 12 on flap 28. This distance is .031 of an inch shorter than the across the wall members formed by panel 15 and panels 13 and flap 17. Therefore, the wall members formed by panels 14 and 16 terminate at the bottom so as to have no overhang and they will receive solid support from flaps 25 and 27. If we had overhang by panels 14 and 16 when the completed container was filled and in transit, it would be subject to a constant vibration. The product carried will apply forces on these panels with a downward component on them, which would cause them to continually roll over score 12 attempting to reach the level of bottom outside surfaces of flaps 25 and 27 and then roll up into position again. This rolling over action on the score line 12 would shortly cause failure in the thin coating surface coating and when liquids were being carried we would have leakage. The present invention discloses a new and improved bottom structure for an infolded bottom which will not permit overhang and can be fabricated on presently available equipment.

When the bottom is made, the container will be in tubular form as shown in FIG. 7 and mounted on a mandrel. The mandrel will terminate at score line 12 and have a flat end. Therefore, when the bottom closure flaps are closed they are over the end of the mandrel. A pressure pad will act on the container bottom closure flaps to assure proper bonding of the bottom. The pressure pad will have such a contour that it will force the bottom flaps against the mandrel end with uniform pressure. This causes part of flap 25 to move closer to the mandrel end because of side seam flap 17 which is bonded to the inside surface of flap 25 and this change in levels is shown by fold line 25'. For the same reason we have fold line 27' where flap 27 folds over the end of tuck-in flap 31.

While the embodiment of the present invention herein disclosed constitutes a preferred form, it is to be understood that other forms might be adapted and still be within the spirit of the disclosed invention.

I claim:

1. A fold-in bottom end closure for a tubular container having,
  - (a) a body portion defined by four substantially rectangular side wall panels,
  - (b) said bottom closure having first and second minor triangular flaps and first and second major flaps,
  - (c) said minor flaps being shorter than at least one of the major flaps,
  - (d) said minor triangular flaps having a base connected to their adjacent wall panel,
  - (e) said base being shorter than the adjacent wall panel width,
  - (f) two pair of trapezium fold-back members with each being connected to one of said minor triangular flaps,
  - (g) each of said trapezium members having one side connected to one leg of a minor triangular flap, one side connected to a major flap, one side connected to a wall panel and the fourth side not connected,
  - (h) said major flaps are connected to the remaining two wall panels,
  - (i) said two minor triangular flaps extend over said end closure,
  - (j) the two major flaps extend over said end closure being below said minor flaps,

- (k) said trapezium members being folded between the major and minor flaps, and
  - (l) said wall panels attached to said minor flaps are positioned over said major panels and supported by them.
2. A fold-in bottom end closure for a tubular container having,
- (a) a body portion defined by four substantially rectangular side wall panels,
  - (b) said bottom closure having a pair of minor flaps 10 and a pair of major flaps,
  - (c) said minor flaps are connected to alternate wall panels and have at least three sides,
  - (d) two pair of trapezium fold-back members each of which are connected to one minor flap, 15
  - (e) the trapezium members have one side connected to one major flap and one side connected to a wall panel,
  - (f) the total distance of a pair of trapezium member's side connected to major flaps is less than the width 20 of the wall panel their mutual minor flap is connected with.
3. A fold-in bottom end closure according to claim 2, having,
- (a) said tubular cross-section being square. 25
4. A blank for a container of foldable sheet material, said blank comprising, in combination,

- (a) a plurality of wall panels,
  - (b) first and second pairs of major and minor bottom closure flaps alternately connected to the wall panels as extensions thereof,
  - (c) said minor flaps being triangular in shape with its base connected to its adjacent wall panel,
  - (d) said minor flap base having a length less than the width of the adjacent wall panel, and
  - (e) two pair of trapezium fold-back members with each member having one leg connected to a minor flap and one leg connected to a wall panel.
5. A blank for a container according to claim 4, having,
- (a) each of said pair of trapezium members having at least one leg connected to a major flap, and
  - (b) the combined length of two legs of trapezium members connected to the major flaps being less than the width of the wall panels the said minor flaps are connected with.
